UNITED STATES PATENT OFFICE.

GEORGE W. SWIFT, JR., OF BORDENTOWN, NEW JERSEY.

GEARING.

1,097,776.

Specification of Letters Patent. Patented May 26, 1914.

Original application filed September 21, 1911, Serial No. 650,492. Divided and this application filed November 13, 1911. Serial No. 660,086.

To all whom it may concern:

Be it known that I, GEORGE W. SWIFT, Jr., of Bordentown, in the State of New Jersey, have invented a certain new and useful Improvement in Gearing, whereof the following is a specification, reference being had to the accompanying drawings.

This application is a division of my application Serial #650,492, filed September 21, 10 1911 for Letters Patent of the United States for an improvement in mechanism for making paper receptacles.

It is the object of my invention to provide mechanism whereby a shaft, for instance 15 the vertical shaft which carries a circular series of paper receptacle holders in the mechanism aforesaid, is positively intermittently turned, stopped, and held temporarily stationary after each turning movement, 20 and my invention includes the various novel features of construction and arrangement hereinafter described, comprising the combination with a driven shaft; of continuously rotary means arranged to turn said 25 shaft, including a crank having a wrist pin roller; a disk on said shaft, having four radial slots adapted to be successively engaged by said wrist pin roller; four stop rollers in a circular series on said disk, concentric with said axis; a stop disk on the 30 axis of said crank, having a circular arc channel concentric with said crank axis and of such circumferential extent as to successively engage said stop rollers when said 35 radially slotted disk is released by said wrist pin roller; whereby said driven shaft is positively intermittently turned quarter revolutions, stopped, and held temporarily 40 stationary after each quarter revolution.

45 In said drawings; Figure I is a fragmentary plan view of a machine conveniently embodying my invention. Fig. II is a fragmentary elevation of the right hand side of said machine as indicated in Fig. I.

50 In said figures; the mechanism is supported on the frame 260 and is driven by suitable gearing engaging the gear 299 on the shaft 300 mounted in the frame bracket 301 and carrying the continuously rotary driven element including the crank arm 302 having the wrist pin roller 303 arranged to successively engage the four radial slots 304 in the intermittently driven element including the disk 305 fixed on the vertical driven shaft 86, 55 which latter supports the circular series of

holders for the paper receptacles in the machine described in my original application aforesaid.

It is to be understood that the arrangement above described is such that by the continuous rotation of said crank 302, said disk 305 is automatically engaged and released by said roller 303, being thus intermittently turned quarter revolutions and left in the position shown in Fig. I. In order to stop 60 and hold said disk 305 after each quarter revolution thereof I provide stop mechanism including the four rollers 307 on said disk, and the channel 308 of the stop disk 309 which is carried by said gear 301 in rigid 65 relation with said crank 302, so as to successively engage said rollers 307.

I do not desire to limit myself to the precise details of construction and arrangement herein set forth as it is obvious that various 70 modifications may be made therein without departing from the essential features of my invention as defined in the appended claims.

I claim:—

1. In mechanism of the class described, 80 the combination with a driven shaft; of continuously rotary means arranged to turn said shaft, including a crank having a wrist pin roller; a disk on said shaft, having four radial slots adapted to be successively engaged by said wrist pin roller; four stop 85 rollers in a circular series on said disk, concentric with said axis; a stop disk on the axis of said crank, having a circular arc channel concentric with said crank axis and 90 of such circumferential extent as to successively engage said stop rollers when said radially slotted disk is released by said wrist pin roller; whereby said driven shaft is positively intermittently turned quarter 95 revolutions, stopped, and held temporarily stationary after each quarter revolution.

2. In mechanism of the class described, 100 the combination with a driven shaft; of continuously rotary means arranged to turn said shaft, including a crank having a wrist pin roller; a disk on said shaft, having four radial slots adapted to be successively engaged by said wrist pin roller; four stop 105 rollers in a circular series on said disk, concentric with said shaft; a stop disk on the axis of said crank, having means arranged to successively engage said stop rollers when said radially slotted disk is released by said wrist pin roller; whereby said driven shaft 110

is positively intermittently turned quarter revolutions, stopped, and held temporarily stationary after each quarter revolution.

3. In mechanism of the class described, 5 the combination with a driven shaft; of rotary means arranged to turn said shaft, including an eccentric wrist pin; a disk on said shaft, having slots adapted to be successively engaged by said wrist pin; stop 10 rollers in a circular series on said disk concentric with said shaft; a stop disk on the axis of said eccentric, having means arranged to successively engage said stop rollers when said slotted disk is released by 15 said wrist pin; whereby said driven shaft is positively intermittently turned quarter revolutions, stopped, and held stationary after each quarter revolution.
4. In mechanism of the class described, 20 20 the combination with a driven shaft; of rotary means arranged to turn said shaft, including an eccentric pin; an element on said shaft, having slots adapted to be successively engaged by said pin; stop rollers in 25 a circular series concentric with said shaft; a stop disk on the axis of said eccentric, hav-

ing means arranged to successively engage said stop rollers when said slotted disk is released by said pin; whereby said driven shaft is positively intermittently turned, 30 stopped, and held stationary after each turning movement.

5. In mechanism of the class described, the combination with a driven shaft; of rotary means arranged to turn said shaft, including an eccentric; an element on said shaft, having slots adapted to be successively engaged by said eccentric; stops carried by said shaft; means carried by said eccentric arranged to successively engage 40 said stops when said shaft is released by said eccentric; whereby, said shaft is positively intermittently turned, stopped, and held stationary after each turning movement. 45

In testimony whereof, I have hereunto signed my name at Bordentown, New Jersey, this tenth day of November, 1911.

GEORGE W. SWIFT, JR.
